UNITED STATES PATENT OFFICE.

FRANÇOIS BAVEREY, OF OULLINS, FRANCE, ASSIGNOR TO SOCIETE DU CARBURATEUR ZENITH, OF LYON, FRANCE.

CARBURETER.

1,176,267.

Specification of Letters Patent. Patented Mar. 21, 1916.

Application filed February 7, 1914. Serial No. 817,274.

To all whom it may concern:

Be it known that I, FRANÇOIS BAVEREY, citizen of the French Republic, residing at 36 Rue Pasteur, Oullins, Rhone, France, 5 have invented new and useful Improvements in Carbureters for Explosion-Motors, of which the following is a specification.

This invention relates to improvements in carbureters with concentric jets of the kind 10 described in Patent No. 907953 of 29th December 1908.

The object of the invention is to effect an energetic stirring of the gaseous mixture in the carbureting chamber in order to assure 15 a homogeneous mixture.

The annexed drawing illustrates the application of the invention to a carbureter comprising two concentric nozzles and shows the same in vertical section.

20 The principal nozzle 1 fed by a constant level fuel containing reservoir is annular, and is provided centrally with a tube 3 open at both ends and communicating with the atmosphere at its lower part. The compensator nozzle 2 fed by the compensator well 5, receiving its supply from the well or reservoir 4, is also annular and concentric with the nozzle 1 and has its orifice at the same level as the orifice of nozzle 1. Immediately 25 above these jets may be arranged a fixed helicoidal baffle plate 6 surrounded by a tube 7. Air passes through the central tube 3 by which the gaseous mixture is stirred; this stirring can be further effected 30 by a gyratory movement given to the mixture by a helical member 6, the gaseous mixture formed by the spirit issuing from the jets and by the central air. This initial mixing assists the homogeneousness of the 35 final explosive mixture formed in the carburation chamber 8 by means of the air flowing round the jets and entering through the ordinary inlet 9.

Instead of sucking air at atmospheric 40 temperature through the central tube 3 the air sucked in through said tube could be more or less heated which would facilitate the vaporization of the fuel at the outlet of the nozzles and in the carburation chamber. 45 By sufficiently heating the air thus sucked in heavy fuels such as petroleum, benzole or the like could be used.

50 What I claim as my invention and desire

to secure by Letters Patent of the United States is:—

55 1. In a carbureter for explosion motors the combination of an annular fuel nozzle, a second annular nozzle axially disposed within said first mentioned fuel nozzle and having its orifice substantially in the same horizontal plane as the orifice of said first mentioned nozzle, a chamber within said second nozzle adapted to supply air to the orifices of said nozzles, and having its orifice in the same horizontal plane as said orifices of 60 said nozzles, and means for stirring and mixing together the fuel and air issuing from said nozzles and said chamber.

65 2. In a carbureter for explosion motors the combination of an annular fuel nozzle, 70 a second annular nozzle axially disposed within said first mentioned fuel nozzle, and having its orifice substantially in the same horizontal plane as the orifice of said first mentioned nozzle, a chamber within said second nozzle adapted to supply air to the orifices of said nozzles, and having its orifice in the same horizontal plane as said orifices of 75 said nozzles, a helicoidal baffle plate, and a tube surrounding said nozzles adapted to 80 guide the fuel and air to said baffle plate.

75 3. In a carbureter for explosion motors, the combination of an annular fuel nozzle, a second annular nozzle axially disposed within said first mentioned fuel nozzle, a 85 chamber within said second nozzle adapted to supply air to the orifices of said nozzles, and means in the form of an inclosed baffle plate for stirring and mixing together the fuel and air issuing from said nozzles and 90 said chamber.

85 4. In a carbureter for explosion motors, the combination of an annular fuel nozzle, means for supplying air axially within said nozzle, a tube removably secured to the 95 nozzle and a helicoidal baffle plate inclosed by the tube and positioned to divide said air axially and cause the same to mix with the fuel fed by the nozzle.

95 5. In a carbureter, for explosion motors, 100 the combination with an annular fuel nozzle, a tube axially thereof and open at both ends for supplying air within said nozzle, a tube secured to the nozzle at the upper end thereof and a baffle plate suspended 105 from above the nozzle axially of the latter

and inclosed by the tube to divide the air and cause the same to mix with the fuel fed by the nozzle.

6. In a carbureter the combination with 5 a carburation chamber; of three concentrically placed and spaced tubes providing a pair of annular nozzles having independent fuel supply channels and an inner tube of relatively large diameter through which air 10 is drawn to commingle with the fuel issuing therefrom, said inner tube being clearly open at both ends.

7. In a carbureter, the combination with 15 a carburation chamber having an inlet; of three spaced tubes arranged axially in said chamber and providing a pair of continuously annular fuel nozzles, means for supplying fuel through independent channels

to said nozzles, the inner tube having free communication with the atmosphere directly at its lower end and means above the upper ends of the tubes to stir and mix the air supplied through the latter tube and the fuel from the nozzles, upon suction being created in the carburation chamber prior 25 to the mixing of said air and fuel in the latter, to assist in the production of a homogeneous explosive mixture in said chamber with the air entering from the inlet.

In witness whereof I have signed this 30 specification in the presence of two witnesses.

FRANÇOIS BAVEREY.
